UNITED STATES PATENT OFFICE.

FREDERICK CHARLES SCOTT, OF DETROIT, MICHIGAN.

CHURN.

1,230,040.

Specification of Letters Patent.

Patented June 12, 1917.

Application filed August 1, 1916. Serial No. 112,616.

To all whom it may concern:

Be it known that I, FREDERICK C. Scott, a subject of the King of Great Britain, residing at Detroit, in the county of Wayne and State of Michigan, have invented a new and useful Churn, of which the following is a specification:

The present invention relates to reciprocating machines of that type, known as churrs, washing machines, and tumblers.

The object of the present invention is to provide a machine in which the receptacle may be easily adjusted to fill and empty the same, and which at the same time can be reciprocated back and forth horizontally and non-rotatably.

My invention has several advantages, one of which is to increase the speed of churning cream into butter, and which will prevent the butter when formed from being sticky. When the machine is used as a tumbler, longer and lighter material may be treated without danger of bending the same for the reason that the material will not turn end over end but simply shift backward and forward in the sawdust.

The above object is accomplished by the present invention, by providing a receptacle for use as the body of the churn, washing machine, or the like, and which is so peculiarly mounted that when operated, the weight of the receptacle and its contents is supported on a frame, and at no time during the operation is it necessary for the operator to support, or work against, the weight of the receptacle. The present invention also embraces a structure wherein the receptacle is pivoted in guides, and adapted to be swung upon the guides into various positions for filling, emptying, and operating the receptacle, and which receptacle has a detachable guide rod to hold the receptacle in the frame in a substantially horizontal position during its reciprocation.

The invention will be best understood from a consideration of the following detailed description, taken in connection with the accompanying drawings forming part of this specification, with the further understanding that while the drawings show a practical form of the invention, the latter is not confined to strict conformity with

the showing of the drawings, but may be changed and modified so long as such changes and modifications come within the scope of the appended claims.

In the drawings:

Fig. 1 is a side elevation of a churn constructed according to the present invention, the dotted lines showing the receptacle swung into vertical position for filling and emptying the receptacle.

Fig. 2 is a top plan view of the same.

Fig. 3 is a detail end view of the receptacle showing the means for fastening the removable cover in place.

Fig. 4 is a transverse section through the receptacle, intermediate its ends, showing the location of anchoring pegs for pins holding clothes, and the like, from longitudinal movement in the receptacle when the device is used for washing clothes.

Fig. 5 is a fragmentary section through one end of the receptacle, taken on line 5-5 of Fig. 3.

Fig. 6 is a detail transverse section through one of the guides for the receptacle, showing the adjacent trunnion with its parts mounted thereon.

Fig. 7 is a similar view, showing a modified form of guide and mounting for the trunnion.

Fig. 8 is a detail transverse section, taken longitudinally through the guide rod socket, showing the means for detachably securing the guide rod therein.

Fig. 9 is a detail section, taken on the line 9-9 of Fig. 2, and showing the bearing for detachably holding the sliding guide rod to the frame.

Referring to the drawings, 10 designates a preferably rectangular frame, supported in a substantially horizontal position by legs 11, and elongated for a purpose which will hereinafter appear.

As shown to advantage in Figs. 6 and 7, the frame is preferably made of angle iron, and upon the opposite sides of the frame are mounted a pair of opposed guides. Each guide, as shown in Figs. 1, 2 and 6, comprises a straight horizontally arranged supporting rail 12 having an upturned flange 13, and supporting upon its opposite ends an upwardly looped guard rail 14.

The guard rail has an inturned flange 15 arranged opposite to the flange 13. As shown in Figs. 1 and 2, the guard rail has its ends turned oppositely from each other 5 and secured upon the upper face at the ends of the supporting rail 12, by machine screws 16, or the like. These screws 16 hold both sections of the guide to the side bar of the frame 10.

10 A receptacle 17 is mounted in the frame and may be of any desired configuration. The receptacle in the present instance is shown as of barrel shape. Trunnions 18 project from the opposite sides of the receptacle 17, intermediate the ends of the latter, and are secured to the receptacle by plates 19 conforming to the side of the receptacle. The trunnions 18 project through 15 the guides and carry rollers 20 loosely and 20 rotatably mounted thereon, which rest upon the supporting rails 12 beneath the guard rails 14, and which are held from lateral displacement by the flanges 13 and 15.

In Fig. 7, I have shown a modified form 25 of antifriction device for the trunnions of the churn. As there shown, the supporting rail 12^a is provided with spaced longitudinally extending grooves 13^a, while the guard rail 14^a is likewise provided with 30 spaced longitudinally extending grooves 15^a. The trunnions have raceways encircling the same in which are retained the ball bearings 20^a. As the barrel is reciprocated, the ball bearings will ride within the longitudinally 35 extending grooves 13^a and 15^a and reduce the friction between the trunnions and the guideways and at the same time keep the trunnions from lateral displacement.

Journalized transversely in the frame 10, 40 and spaced from the receptacle 17 is a crank shaft 21, which has like crank portions at its opposite ends in registry with the trunnions 18, as clearly shown in Fig. 2. Connecting rods 22 are hinged to the crank 45 portions of the shaft 21 and are pivoted upon the trunnions 18, preferably at the inner sides of the frame 10. By turning the shaft 21, by a handle 23, or other suitable 50 operating means, the receptacle is reciprocated back and forth in the longitudinally extending guides.

A pulley or balance-wheel 24 may be mounted on the shaft 21 to insure the steady rotation of the shaft and prevent jar upon 55 the handle 23, and the pulley 24 itself may be driven in any suitable manner to rotate the shaft 21. As shown in Figs. 3 and 5, the receptacle 17 is open at one end, and provided therewith a ring 25 fitted over 60 the edge of the receptacle and held thereto by screws, or the like.

An inwardly extending flange or ledge 26 is formed on the ring and provides a seat

for a rabbeted cover 27 closing the open end of the receptacle. The cover 27 carries upon 65 its outer face a centrally disposed socket plate 28, in which is threaded a thumb-screw 29 beneath the head of which is pivoted a clamping arm 30.

The ring 25 carries pairs of opposed apertured lugs or sockets 31, in each pair of which are hinged the opposite ends of opposed bails 32, adapted to be turned down against the socket plate 28 of the cover and bound thereon by the clamping arm 30, the latter being held tight against the bails by the thumb-screw 29.

When the receptacle 17 is reciprocated back and forth, it is held to a horizontal path, as shown in full lines in Figs. 1 and 2, by a socket plate 33, mounted on the closed end of the receptacle, and in which is detachably fitted one end of a guide rod 34, best shown in Fig. 8. A thumb-screw 35, or other suitable device, is threaded in one side of the socket and binds the guide rod 34 therein. The guide rod 34 extends outwardly over the adjacent end of the frame 10 and fits in a bearing. As may be seen from Fig. 9, this bearing comprises a base 90 part 36 secured to the frame 10 and a hinged part 37 held in closed position about the rod 34 by a thumb-screw 38.

The guide rod 34 holds the receptacle 17 from turning upon the trunnions 18, and restricts the receptacle to a straight path. When it is desired to tilt the receptacle to raise the covered end thereof for placing articles or material in the receptacle, or for swinging the covered end downwardly to 100 dump or pour the contents from the receptacle, the thumb-screw 35 is released from the guide rod 34, and the latter is retracted from the socket 33. The receptacle 17 may now be swung in the desired direction. 105

The receptacle 17 may be provided with a plurality of inwardly extending pegs or pins 39.

It is apparent that this machine may be used as a churn, as a washing machine, or as a tumbler for smoothing or polishing articles with sawdust, sand, or the like. 110

The bearing or connection between the guide rod 34 and the frame 10 is detachable to permit the use of the rod 34 as a handle 115 in swinging the receptacle 17 into various positions for emptying the same. The detachable connection between the guide rod 34 and the closed end of the receptacle permits the swinging of the receptacle independently of the guide rod for filling the receptacle. 120

As shown in Fig. 2, the receptacle 17 is provided with a hook 40 at one side adapted for engagement in an eye 41 mounted on the 125 frame, the hook and eye being adapted to

hold the receptacle in a substantially vertical position, as shown in dotted lines in Figs. 1 and 2.

What is claimed is:—

5 1. In a churn, a frame provided with horizontally arranged elongated guides, a receptacle having trunnions pivotally and slidably mounted on said guides, means for reciprocating said receptacle back and forth on said guides, and means for maintaining

10 said receptacle against rotation on its trunnions during the reciprocation thereof and allowing the pivotal movement thereof for filling and emptying the receptacle when desired.

15 2. In a churn, a frame, an elongated receptacle having a trunnion mounting intermediate its ends in the frame, means for reciprocating the receptacle longitudinally of the frame, and a guide rod connecting the receptacle to the frame to hold the receptacle to a straight horizontal path during its reciprocation, said guide rod being detachable to permit the free swinging of the receptacle into various positions for filling and emptying the receptacle.

20 3. In a churn, a frame, guides mounted on opposite sides of the frame, a receptacle fitting in the frame and having trunnions slidably and rotatably engaging said guides, and anti-friction means rotatably carried by the trunnions and engaging the guides for holding the receptacle from lateral movement in the frame.

25 4. A churn comprising a frame, a receptacle having trunnions intermediate its ends, longitudinally extending guides on the side of the frame adapted to receive the trunnions and pivotally and slidably support

30 the receptacle in the frame, means for reciprocating said receptacle on said guides, and a detachable guide rod connected to one end of the receptacle and having sliding engagement with one end of the frame to hold

35 the receptacle to a straight path longitudinally of the frame during the reciprocation of the same, to prevent the rotation thereof and to permit the receptacle to be swung for adjustment out of longitudinal alignment with the frame.

40 5. A churn comprising a frame, longitudinal guides mounted upon the sides of the frame and comprising lower and upper parts, a receptacle in the frame having trunnions mounted in the guides, means for reciprocating the receptacle, and anti-friction supporting means rotatably mounted upon the trunnions and engaging the upper and lower parts of the guides for supporting the receptacle and for retaining the receptacle from shifting laterally.

45 6. A churn comprising a frame, opposed longitudinal guides mounted in the frame

and comprising upper and lower parts having inturned flanges at their edges, a receptacle in the frame having trunnions for engagement in the guides, rollers loosely mounted on the trunnions and fitting between the upper and lower parts of the guides and adapted to bear against said inturned flanges to hold the receptacle from lateral shifting, and means for reciprocating the receptacle.

50 7. A churn comprising a frame, elongated guides mounted longitudinally on the opposite sides of the frame, a receptacle in the frame provided with trunnions projecting through said guides, anti-friction devices loosely mounted on the trunnions and engaging said guides to support the trunnions and prevent lateral shifting of the receptacle, and means for reciprocating said receptacle on said guides said receptacle being adapted to swing upon the trunnions into various angular adjustments in the frame.

55 8. A churn comprising a frame, a receptacle having means slidably and pivotally connecting it to the frame and adapted to be swung about a horizontal axis into various positions in the frame, a removable cover on one end of the receptacle, means for holding the receptacle in vertical position for filling and emptying the receptacle, guiding means between the receptacle and the frame for holding the receptacle to a path in longitudinal alignment with the frame and against rotation, and means for reciprocating the receptacle longitudinally in the frame.

60 9. In a churn, a frame, a receptacle having a trunnion mounting in the frame, means for reciprocating the receptacle, a guide rod carried by the receptacle and slidably engaging the frame to hold the receptacle to a straight path longitudinally in the frame and against rotation, a detachable connection between the guide rod, and the frame to permit swinging of the receptacle by the guide rod, and a second detachable connection between the guide rod and the receptacle to permit swinging of the receptacle independently of the guide rod.

65 10. In a churn, a frame, provided with horizontally arranged elongated guides, an elongated receptacle provided with trunnions arranged centrally thereon, pivotally and slidably mounted in said guides and arranged lengthwise of the frame, means for reciprocating said receptacle back and forth on said guides, a cover for one end of said receptacle, anti-friction devices loosely mounted on said trunnions and interposed between the same and said guides, and detachable means for maintaining said receptacle against rotation around its trun-

nions as an axis and to keep the same in a horizontal position during the reciprocation thereof, but to allow when detached the pivotal movement thereof around its axis for filling and emptying the receptacle, as desired.

In testimony, that I claim the foregoing

as my own, I have hereto affixed my signature in the presence of two witnesses.

FREDERICK CHARLES SCOTT.
